CLAMPING ARRANGEMENT FOR A COMBINED SQUEEGEE AND SPONGE DEVICE

Maurice J. Epstein, University Heights, Ohio, assignor to
Dorothy Epstein, University Heights, Ohio

Filed June 13, 1973, Ser. No. 369,433

Term of patent 14 years

Int. Cl. D7—05

U.S. Cl. D7—178

FIG. 1

FIG. 2

FIG. 3

FIG. 4

FIG. 5

FIG. 1 is a perspective view of a clamping arrangement for a combined squeegee and sponge device;

FIG. 2 is a side elevational view thereof;

FIG. 3 is a top elevational view thereof;

FIG. 4 is a front elevational view thereof; and

FIG. 5 is a rear elevational view thereof.

The portions of the squeegee, sponge and handle shown in dotted lines are for illustrative purposes only and form no part of the design.

I claim:

The ornamental design for a clamping arrangement for a combined squeegee and sponge device, as shown and described.
